R. B. GILCHRIST

DRINK MIXER

Filed March 8, 1922

Patented Aug. 21, 1923.

1,465,630

UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 8, 1922. Serial No. 541,910.

To all whom it may concern:

Be it known that I, RAYMOND B. GILCHRIST, a citizen of the United States, and a resident of Newark, in the county of Essex 5 and State of New Jersey, have invented certain new and useful Improvements in Drink Mixers, of which the following is a full, clear, and exact description.

The invention relates to drink mixers.

- 10 In machines for this purpose, the liquid constituents of the drink to be mixed are usually poured into a receptacle which is generally designated a "shaker," from many different containers disposed away from the 15 mixer. The receptacle with these constituents therein is brought to the mixer and placed in operative relation thereto and is removed from the machine after each mixing operation to discharge its contents. 20 This is rendered necessary, because so many different ingredients and flavors are used in making drinks that they are, in nearly all cases, mixed individually. It is usually necessary to run the agitator for a considerable 25 period to properly blend or mix the constituents and, therefore, it is desirable that provision be made for retaining the receptacle and agitator in operative relation to permit the dispenser to perform other 30 duties during the mixing operation. In drink mixing, it thus becomes necessary to frequently place the receptacle, containing the constituents, into cooperative relation to the agitator and to withdraw it from the 35 machine to discharge its contents and cleanse the receptacle between mixing operations.

A desideratum in this art is to expedite and simplify the operations necessary to 40 bring the receptacle and agitator into cooperative relation, to maintain them in such relation, in starting and stopping of the motor and the removal of the receptacle. Heretofore, in machines whereof I am 45 aware excepting those exhibited by me in pending applications for patents, it has been necessary in their use to manually manipulate the receptacle into operative position and withdraw it therefrom and to additionally perform some separate step or operation, such as lowering the motor and agitator together, or shifting the agitator and its shaft into the receptacle and relatively 50 to the motor, or raising and locking a recep-

tacle support to establish and maintain cooperative relation of the receptacle and agitator or to control the operation of the machine. Another desideratum in this art is to simplify the machine by dispensing with movable connections in and for the mechanism for driving the agitator.

One object of the present invention is to provide an improved drink mixer in which these additional operations or steps are dispensed with and in which manual shift of the receptacle is utilized to completely control the operation of the machine and the securing of the receptacle and the agitator in cooperative relation. By dispensing with the necessity of these additional steps or 70 operations, the time of the dispenser in performing them is saved and the service is improved.

Another object of the invention is to provide a receptacle controlled machine which 75 is equipped so that the receptacle can be manipulated to control its locking into operative position around the agitator, its release for withdrawal, and the starting and stopping of the motor. 80

Another object of the invention is to provide a machine of this type in which movable connections in and for the driving mechanism for the agitator are dispensed with.

Another object of the invention is to provide a machine which is simple in construction, which may be easily and readily operated and which is efficient in operation.

Other objects of the invention will more 90 fully appear from the following description.

The invention consists in the several novel features hereinafter set forth and more particularly defined by claims at the conclusion hereof.

In the drawings: Fig 1 is a vertical section of a machine embodying the invention, parts being shown in elevation. Fig. 2 is a rear elevation. Fig. 3 is a horizontal section 100 on line 3—3 of Fig. 1. Fig. 4 is a detail of the upper portion of the slot in the supporting standard.

The invention is exemplified in a machine comprising an electric motor which is secured to the upper end of a supporting standard 9. The latter is rigidly secured to a base 10 by a bolt 10^a, which is adapted to 105

rest on a counter or table. An agitator shaft 11 projecting downwardly from, and secured to, the rotor of the motor 8, is provided at its lower end with an agitator 12 of 5 suitable construction, as well understood in the art. Shaft 11 has fixed relation to the rotor of the motor 8, thus avoiding a sliding connection for permitting the agitator to be raised and lowered into the receptacle 10 19 which contains the material to be mixed. There is sufficient clearance below and around the agitator to permit the receptacle to be placed into operative position from below and without moving the agitator. The 15 case of motor 8 is rigidly secured to the upper end of standard 9 by screws 13 which extend through a block 14. A case 15, containing a snap-switch of usual construction with members connected to control the motor 20 8, is fixedly secured to the block 14 and is provided with a lever 16 which is of the snap-type and spring-pressed into both of the alternate positions into which it is shifted, as well understood in the art, so 25 that it will remain in one position until it is reversely shifted to the other.

The front face 18 of standard 9 is arcuate in cross section, conforming substantially to the periphery of the receptacle 19 which 30 may, if desired, be provided with upper and lower wear or reinforcing bands 21, 21^a. This arcuate face extends vertically to form a stationary guide on which the receptacle 19 may slide into and out of operative relation with the agitator 12. Receptacle 19 is provided with a stud which is fixed thereto and projects from the outer side thereof and comprises a shank 23 and an enlarged head 24 adapted to form an interlock with the 35 supporting standard or guide and lock the receptacle against forward, backward and lateral movement while the receptacle is being manually supported and raised and lowered into and out of operative relation 40 with the agitator. For this purpose, the standard 9 is provided with a vertical slot 25 of restricted width and in which the shank 23 of the stud is adapted to slide vertically, and an opening or enlarged lower 45 50 terminal 26 to permit the head 24 to pass through the standard during the insertion of the shank 23 of the stud into the slot 25 and its removal therefrom. When the stud is raised above the opening 26, it will cause 55 the receptacle to be locked against horizontal movement in any direction, the head 24 lapping and being confined by the back of the standard 9 and the stud-shank 23 being held against rearward movement by engagement 60 by the receptacle with the front face of the standard 9. At its upper end, slot 25 is provided with a lateral offset 27 which is adapted to receive the stud-shank 23 when the receptacle is rotated on its own axis to cause 65 the stud to be vertically locked and thus

secure the receptacle in cooperative relation to the agitator.

A lever 29 is pivoted, at 30, to the back of the standard 9, and has a forked upper end 31 adapted to shift the switch-lever 16 from either of its alternative positions to the other. The lower end of this lever is formed with an open ended cam-slot 32 which is normally disposed, as indicated by dotted lines in Fig. 2, so that the head 24 of the upwardly moving stud on the receptacle will enter it and shift the lever into position to operate switch-lever 16 to close the circuit for the motor 8 while the vessel is being lifted to its operative position and so that, while the receptacle is being lowered, the head will reversely shift lever 29 to operate switch-lever 16 to stop the motor. The upper end of the slot 32 is enlarged or cut away, as at 33, so that the rotation of the receptacle and movement of the stud to lock the receptacle will not shift the lever and will cause the motor to run while the receptacle is thus locked. 75 80 85

In operation, the operator will place the receptacle 19 against the lower portion of standard 9 and insert the stud into the enlarged portion 26 of the guide-slot in the standard, then manually lift the receptacle until the stud-shank 23 encounters the upper end of slot 25, and then rotate the receptacle slightly, to position the shank of the stud in the offset 27 of the guide-slot, whereupon, the receptacle will be locked so that the agitator will be in operative relation to the receptacle and its contents. During the lifting of the receptacle, it will be manipulated, supported and locked against lateral movement by the guide and stud, and the head 24 will enter slot 22 in lever 29, engage one of its sides and shift said lever into position shown by full lines in Fig. 2. This will shift the switch-lever 16 into position to close the circuit for the motor 18 and cause it to run until the receptacle is removed. 90 95 100 105 110 After the mixing operation has been completed, the operator will grasp the receptacle, rotate it slightly to release the stud-shank from the offset 27 of slot 25 and lower the receptacle. In lowering the receptacle, the head 24 of the stud will shift lever 29 into position shown by dotted lines in Fig. 2, so that the upper end of the lever will snap the switch-lever 16 into position to open the circuit and cause the motor to stop. During 115 the lowering movement of the receptacle, it will be horizontally locked to the guide-standard, so that there will be no danger of striking the receptacle, until the stud passes into the opening 26, whereupon, the receptacle will be free to be withdrawn and emptied of its mixed contents. 120 125

The invention exemplifies a mixing machine in which the relationship of the agitator and motor is substantially fixed and 130

in which the motor is fixed and which is controlled by placement of the receptacle into and out of operative relation to the agitator; in which means is provided to positively guide the receptacle while it is manually supported and being shifted into and out of cooperative relation with the agitator; which is simple in construction; and in which the receptacle becomes locked in and 10 unlocked from its operative position by rotative manipulation of the receptacle itself.

The invention is not to be understood as restricted to the details set forth, since these may be modified within the scope of the appended claims, without departing from the spirit and scope of the invention.

Having thus described the invention, what I claim as new and desire to secure by Letters Patent, is:

20 1. In a machine of the character described, the combination of a support, a motor, an agitator driven by the motor and supported from above with sufficient clearance to permit a receptacle with an open 25 top to be placed into operative position around the agitator, a slideway for directing the receptacle while it is manually supported and is being shifted into operative 30 position, and means to lock the receptacle to the slideway while it is being manually shifted into said position.

2. In a machine of the character described, the combination of a support, a motor, an agitator driven by the motor and supported from above with sufficient clearance 35 to permit a receptacle with an open top to be placed into operative position around the agitator, a slideway for directing the receptacle while it is manually supported and is being shifted into operative position, and means to lock the receptacle to the slideway while it is being manually shifted 40 into and out of said position.

3. In a machine of the character described, the combination of a support, a motor, an agitator driven by the motor and supported from above with sufficient clearance to permit a receptacle with an open 45 top to be placed into operative position around the agitator, a stationary guideway for directing the receptacle while it is manually supported and is being shifted into operative position, and means to lock the receptacle to the guideway while it is being 50 manually shifted into and out of said position.

4. In a machine of the character described, the combination of a support, a motor, an agitator driven by the motor and supported from above with sufficient clearance 55 to permit a receptacle with an open top to be placed into operative position around the agitator, means to vertically guide the receptacle while the receptacle 60 itself is manually gripped and supported

and being shifted into and out of operative position, and an interlocking connection between the receptacle and the guide for holding the receptacle against lateral movement while it is being shifted into and 70 out of operative position.

5. In a machine of the character described, the combination of a support, a motor, an agitator driven by the motor and supported from above with sufficient clearance 75 to permit a receptacle with an open top to be placed into operative position around the agitator, means to vertically guide the receptacle while the receptacle itself is manually gripped and supported and being shifted into and out of operative 80 position, and an interlocking connection between the receptacle and the guide-means for holding the receptacle against lateral movement during said shift and for 85 holding it in operative position.

6. In a machine of the character described, the combination of a support, a motor, an agitator driven by the motor and supported from above with sufficient clearance 90 to permit a receptacle with an open top to be placed into operative position around the agitator, stationary means to vertically guide the receptacle while it is manually supported and is being shifted 95 into and out of operative position, and an interlocking connection between the receptacle and the guide-means for holding the receptacle against lateral movement while it is being shifted into and out of operative 100 position.

7. In a machine of the character described, the combination of a support, a motor, an agitator driven by the motor and supported from above with sufficient clearance 105 to permit a receptacle with an open top to be placed into operative position around the agitator, an interlocking stud-and-slot connection between the support and the receptacle.

8. In a machine of the character described, the combination of a support, a motor, an agitator driven by the motor and supported from above with sufficient clearance 110 to permit a receptacle with an open top to be placed into operative position around the agitator, a slideway for the receptacle while it is manually supported and is being shifted into operative position, an interlocking stud-and-slot connection between 115 the slideway and the receptacle.

9. In a machine of the character described, the combination of a support, a motor, an agitator driven by the motor and supported from above with sufficient clearance 120 to permit a receptacle with an open top to be placed into operative position around the agitator, a stationary guideway for slidably guiding the receptacle while 125 manually supported and shifted into opera- 130

tive position, a slidable stud-and-slot connection between the guide-way and the receptacle.

10. In a machine of the character described, the combination of a support, a motor, an agitator driven by the motor and supported from above with sufficient clearance to permit a receptacle with an open top to be placed into operative position around the agitator, and means to secure the receptacle in operative position adapted to be rendered operative by rotation of the receptacle.

11. In a machine of the character described, the combination of a support, a motor, an agitator driven by the motor and supported from above with sufficient clearance to permit a receptacle with an open top to be placed into operative position around the agitator, means for slidably guiding the receptacle while it is manually supported and is being shifted into operative position, and means to secure the receptacle in operative position adapted to be rendered operative by rotation of the receptacle.

12. In a machine of the character described, the combination of a support, a motor, an agitator driven by the motor and supported from above with sufficient clearance to permit a receptacle with an open top to be placed into operative position around the agitator, stationary means for slidably guiding the receptacle while it is manually supported and is being shifted into operative position, and means to secure the receptacle in operative position adapted to be rendered operative by rotation of the receptacle.

13. In a machine of the character described, the combination of a support, a motor, an agitator driven by the motor and supported from above with sufficient clearance to permit a receptacle with an open top to be placed into operative position around the agitator, a guide for slidably guiding the receptacle while manually supported and shifted into operative position, and an interlock for holding the receptacle against lateral movement while it is manually supported and being shifted into and out of its operative position comprising an element on and projecting from the side of the receptacle.

14. In a machine of the character described, the combination of a support, a motor, an agitator driven by the motor and supported from above with sufficient clearance to permit a receptacle with an open top to be placed into operative position around the agitator, and a locking device to secure the receptacle in operative position comprising an element on and projecting laterally from the side of the receptacle.

15. In a machine of the character de-

scribed, the combination of a support, a motor, an agitator driven by the motor and supported from above with sufficient clearance to permit a receptacle with an open top to be placed into operative position around the agitator, means for slidably guiding the receptacle while it is manually supported and is being shifted into operative position, and an interlocking device for holding the receptacle, comprising an element on and projecting from the side of the receptacle and extending through said guiding means.

16. In a machine of the character described, the combination of a support, a motor, an agitator driven by the motor and supported from above with sufficient clearance to permit a receptacle with an open top to be placed into operative position around the agitator, automatic means for securing the receptacle in operative position, means for controlling the operation of the motor, and a stud movable with the receptacle, for operating said controlling means.

17. In a machine of the character described, the combination of a support, a motor, an agitator driven by the motor and supported from above with sufficient clearance to permit a receptacle with an open top to be placed into operative position around the agitator, means for slidably guiding the receptacle for securing it in operative position, comprising a stud and means for controlling the operation of the motor operable by said stud.

18. In a machine of the character described, the combination of a support, a motor, an agitator driven by the motor and supported from above with sufficient clearance to permit a receptacle with an open top to be placed into operative position around the agitator, a guideway for the receptacle while it is manually supported and is being shifted into operative position, means for securing it in operative position comprising a stud extending through said slot, and means for controlling the operation of the motor operable by said stud.

19. In a machine of the character described, the combination of a support, a motor, an agitator driven by the motor and supported from above with sufficient clearance to permit a receptacle with an open top to be placed into operative position around the agitator, means for slidably guiding the receptacle, means for securing it in operative position comprising a stud, and means for controlling the operation of the motor comprising a lever having lost-motion and cam connection with said stud.

Signed at Newark, N. J., this 11th day of February, 1922.

RAYMOND B. GILCHRIST.
